UNITED STATES PATENT OFFICE.

BRUCE J. DAVIDSON, OF MARSEILLES, ILLINOIS, ASSIGNOR TO WIREBOUNDS PATENTS COMPANY, A CORPORATION OF MAINE.

MACHINE FOR USE IN MAKING BOXES, CRATES, AND THE LIKE.

Application filed October 29, 1920. Serial No. 420,414.

To all whom it may concern:

Be it known that I, BRUCE J. DAVIDSON, a citizen of the United States, and a resident of Marseilles, in the county of La Salle, in the State of Illinois, have invented new and useful Improvements in Machines for Use in Making Boxes, Crates, and the like, of which the following is a specification.

The invention relates to machines for use in fastening heads, ends, partitions or the like to boxes, crates, and the like.

Among other objects the invention is intended to provide certain improvements contributing to efficiency of operation and practicability of construction of such machines.

The invention will be clearly understood from the following description with reference to one form of machine containing an embodiment of the invention which is shown for illustration in the accompanying drawings.

In said drawings:

Fig. 1 is a side elevation of the illustrative machine, parts thereof being broken away and other parts being shown in section to better illustrate the mechanism, said figure also shows a box, partly broken away, in position to be operated upon.

Fig. 2 is a rear elevation of the illustrative machine showing the main operating shaft and cams.

Fig. 3 is a top plan view of the stapling arm and mechanism carried thereby.

Fig. 4 is a sectional view taken on the line A—A of Fig. 3.

Fig. 5 is a top plan view of the nose of the clincher arm taken at B—B in Fig. 4.

Figs. 6, 7 and 8 are enlarged side views in section of the nose of the stapling arm showing the staple cutting, forming and driving mechanisms in different phases of operation.

Fig. 9 is a top plan view taken on line C—C of Fig. 6.

Fig. 10 is a top plan view of the staple former.

Fig. 11 is a sectional side elevation of the same.

Fig. 12 is an end elevation of the same.

Figs. 13 and 14 are sectional views taken on the line D—D of Fig. 4 showing the staple driver in different phases of its operation.

Figs. 15, 16 and 17 are detailed views of the staple driver being, respectively, a top plan view, an end elevation and a side elevation.

Figs. 18, 19 and 20 are sectional views taken on the line E—E of Fig. 4, showing the cutting mechanism in different phases of its operation.

Fig. 21 is a diagrammatic plan showing a box in different positions on the machine indicating the operation of stapling the box head or end along sides of the box. For clearness of illustration, the lid or cover of the box is not shown in this figure or in Figure 22.

Fig. 22 is an end elevation of the end of a box showing the end section stapled to the cleats of side sections.

The illustrative machine comprises, generally, a staple forming and driving mechanism for forming staples and driving them into the work; and clinching or clamping mechanism to hold the box parts in position during a staple driving operation and to clinch the ends of staples which may be driven through the work.

The staple forming and driving mechanism is carried by the arm 2 supported by the frame 1.

A staple driver 5 operates at the end of arm 2 to drive the staples from the nose of the arm, which is so formed as to permit the driving of staples close to the box sides and in the corners and to gauge the stapling point from the box sides.

The staple is formed at the nose of the arm 2 directly above the staple driver 5 and is driven from that position into the work thus eliminating the use of a staple holder or carrier to transfer the staple from the place where it is formed to the place where it is driven.

In stapling box heads or ends, the preferable practice is to drive the staples upwardly from within the box in order that the operator may more readily manipulate the box and observe the operation. The illustrative machine is designed accordingly; the stapling arm 2 affording a support for the box head or end and the staple driver being arranged to drive the staple upward from the nose of said arm into the box heads or ends and close to the sides.

The staple is formed from staple wire 4.

carried by a reel 6 and fed to the staple forming mechanism by feed rollers 7 and 8 operated by any suitable mechanism, for instance, by the ratchet 9 and pawl 10.

- 5 Before reaching the nose of arm 2 one end of the staple wire 4 is bent upward at a right angle to the main body of the wire thus forming one leg of the staple so that, as shown in Fig. 6, when the wire reaches 10 the nose of arm 2 a staple is partially formed and in position to be driven. When the wire reaches the nose of arm 2 with one leg of the staple formed and upstanding the wire is severed and the formation of the staple completed by a former 11 which bends the severed portion of the wire upward about a spring pressed movable loop bar 12 which has moved into position behind the first formed leg of the staple. Thus the staple 15 is formed pointing up at the nose of the arm 2 in position to be driven into the work by the driver 5, which moves the loop bar 12 out of line as hereinafter explained.

For forming the first leg of the staple 20 before it reaches the nose of arm 2 a stationary loop bar 13 is provided under which the wire 4 is fed and about which it is bent upward by the former 11. Thus it will be noted that the former 11 operates on wire 25 for two staples at each upward reciprocation, that is, at each reciprocation it completes one staple about the movable loop bar 12 and partially forms another staple about the stationary loop bar 13.

30 The staple wire 4 is severed by relatively movable knives 14 and 15 carried respectively by arms 16 and 17 pivotally supported by arm 2 at 18 and 19 respectively. Said knives 14 and 15 are normally separated to permit the staple former 11 to pass up and down between them and are closed upon the wire at intervals to perform a severing operation. The operating mechanism for closing the knives 14 and 15 is 35 designed to operate after a feed of staple wire is completed and just prior to the upward stroke of the former 11. After a severing operation the former is raised and the knives are separated by coaction of cam surfaces 20 carried by the former 11 and cam surfaces 21 carried by the arms 16 and 17. After the former 11 has formed the staple about loop bar 12 the driver rises and through the action of cam surface 22 forces 40 loop bar 12 to one side and drives the staple upward into the work. Loop bar 12 is carried by pivoted arm 23 which, as shown in Figures 13 and 14, is so formed that the cam surface 22 of the driver forces the bar

45 to one side during a driving operation and holds it in said position for a sufficient length of time after a driving operation to permit the wire for the next staple to be fed forward to the nose of the arm 2, after which 50 the bar 12 through the action of spring 12^s

snaps behind the leg of the staple which has previously been formed about the loop bar 13 and fed forward to the driving point.

Referring to Figure 3 it will be noted that the staple wire 4 is fed along the longitudinal center line of the stapling arm 2 and that the staples are formed with the plane of their legs parallel to said line. It will also be noted that the sides of the arm 2 are also parallel to the longitudinal center line of the arm 2 and that the driving point is equidistant from either side of said arm. This is particularly advantageous in that it enables the operator to properly position and gauge the stapling operation, the sides 55 of the arm 2 acting as work controlling means to position the side of a box pressed thereagainst and, as shown in Figure 21, enabling the operator to keep the side cleats of the box parallel with the longitudinal center line of the arm 2 and the plane of the staples, thus permitting the driving of staples in the manner shown in Figure 22. It will be noted that, as shown in Figure 22, the staples on opposite sides of the box are 60 driven crosswise the grain of the head or end sections thus more securely retaining the parts together.

It will also be noted that preferably the staple wire is severed at such an angle and the staple is formed in such a manner that when driven into the work the legs will deflect in the same direction and in a plane parallel with the plane of the staple. This is advantageous in assisting to prevent the 65 points from running out at the sides of the work and to increase the holding power of the staples.

The mechanism described may be actuated from driving shaft 25 by any suitable means, for example, by the instrumentalities shown in the drawings, which will now be described.

The staple driver 5 is operated by a fulcrumed lever 5^a having its forward end suitably connected to the staple driver, for instance, by a pin and slot connection 5^b and having its rear end provided with a roller 5^c engaged by a cam 5^d on the shaft 25 said cam having a projection to operate the lever to give the staple driver a quick up stroke and allow its proper return, through the action of spring 5^e, to control the action of the movable loop bar 12.

The knives 14 and 15 for severing the 75 staple wire which are carried by the arms 16 and 17 respectively are operated by a fulcrumed lever 14^a the forward end of which is adapted when raised, to spread the lower extremities of arms 16 and 17, as shown in Figure 19, thus causing knives 14 and 15 to coact and sever the wire therebetween. Lever 14^a is actuated by a cam 14^b on shaft 25 which contacts with a roller 14^c carried 80 at the rear end of lever 14^a. Roller 14^c is 85

held in contact with cam 14^b by spring 14^a. The staple former 11 which rises after a wire severing operation is operated by a fulcrumed lever 11^a having its forward end 5 suitably connected to the staple former, for instance, by a pin and slot connection and having its rear end provided with a roller 11^b engaged by a cam 11^c on the shaft 25, said cam having a projection to operate the lever to give the former a quick up stroke and allow its return through the action of spring 11^d.

The staple wire feed mechanism is operated by the pawl 10 and ratchet 9, the pawl 15 being carried by a lever 10^a journaled on the shaft of feed wheel 8 and reciprocated by connecting rod 10^b from lever 10^c pivoted at 10^d and which carries at its upper end a roller 10^e engaged by cam 10^f on shaft 20 25 to operate the lever to feed the wire, the return motion of the lever being effected by the spring 10^g.

As will be understood, the cams are so timed and the arrangement of the parts is 25 such that in each cycle or revolution of the shaft 25 the lever 14^a moves upward causing a wire severing operation; the former then moves upward separating the cutting knives and forming staple legs; the driver then 30 advances forcing the movable loop bar 12 to one side and drives the completed staple into the work. As the driver and former descend, the staple which has been partially formed on the loop bar 13 is advanced to 35 the nose of the machine, the loop bar 12 snaps into position behind the partially formed staple and the parts are in position for another operation.

Referring to Figures 1 and 4 a clamping 40 and clinching device to cooperate with the staple driver, is carried at the end of arm 3. This device as shown consists of a vertical plunger 30 provided with a rack 31 meshing with a segmental gear 32 pivoted 45 at 33. The segmental gear 32 is provided with an arm 34 to which is pivoted a link 35 connected to a cam lever 36 pivoted at 37 and carrying a roller 38 engaging a cam 39 carried by the shaft 25, said roller being 50 held against said cam by a spring 40. The link 35 is provided between its ends with a turnbuckle 41 by means of which it may be lengthened or shortened, as may be desired. At each rotation of the shaft 25 the plunger 55 30 is lowered to cooperate at the proper time with the staple driver to clamp the box head or end during a stapling operation and to serve as an anvil or clincher to oppose the action of the staple driver and 60 clinch the ends of staples which may be driven through the work. The timing should be such that the plunger clamps the work before the staple is driven. The plunger rises and releases the work after 65 the driving of each staple, enabling the

operator to move the box on the stapling arm the required distance for driving the next staple.

It will be noted that the nose of the arm 3 which carries the clamping and clinching mechanism, like the nose of the stapling arm 2, is so formed as to permit it to be inserted within the box and into the corners and close to the sides thereof, thus permitting either or both arms to operate within 75 the box.

The manner of using the machine will be clearly understood by those skilled in the art, and is indicated in Figures 1 and 21 of the drawings, showing an ordinary wire-bound box with foldably connected side and bottom sections provided with cooperating end cleats and heads or ends arranged inside the cleats to be stapled thereto. In performing the stapling operation, the end 80 or head rests upon the stapling arm as shown in Figure 1 and the operator manipulates the box on said arm while operating the machine successively to drive a row of staples through each cleat; that is to say, 85 through the head or end board along lines which cause the staples to pass into the cleats, and in this operation the nose and sides of the stapling arms serve as guides for enabling the operator to position the 90 work and to gauge the staples from the box sides.

Power for operating the machine may be applied in any suitable manner, as for instance, by the power pulley 45 shown in 100 Figure 2 which may be controllably clutched to the shaft 25 by any suitable clutch mechanism.

Obviously the present invention is not limited to the specific embodiment illustrated and described, which may be variously modified in details of construction and arrangement, and features of the invention may be used in various machines embodying 105 the invention, and in various combinations and sub-combinations.

Having described the invention what is claimed is:

1. A machine for use in fastening heads, 115 ends, partitions or the like to boxes comprising, in combination, a stapling arm adapted to operate within a box; wire severing means; a staple former adapted to perform operations on a plurality of staples simultaneously; and a staple driver.

2. A machine for use in fastening heads, 125 ends, partitions or the like to boxes, and which is adapted to operate within a box comprising, in combination, a staple former adapted to form one leg of each of a plurality of staples at each operation; and a staple driver.

3. A machine for use in fastening heads, 130 ends, partitions or the like to boxes, and which is adapted to operate within a box

- 1 comprising, in combination, a staple former adapted at each operation to partially form one staple and complete the formation of another; and a staple driver.
- 5 4. A machine for use in fastening heads, ends, partitions or the like to boxes, and having an arm adapted to enter a box which comprises means to feed a partially formed staple to the nose of said arm; means to 10 complete the formation of said staple at the nose of said arm; and means to drive the staple from the nose of said arm.
- 15 5. A machine for use in fastening heads, ends, partitions or the like to boxes and having a stapling arm adapted to enter a box comprising, in combination, means to feed staple wire to the nose of said arm; means to partially form a staple from said wire while it is being advanced to the nose 20 of said arm; and means to complete the formation of the staple at the nose of said arm.
- 25 6. A machine for use in fastening heads, ends, partitions or the like to boxes and having a stapling arm adapted to enter a box comprising, in combination, means to feed staple wire to the nose of said arm; means to form one leg of a staple on said wire before it reaches the nose of said arm; means to complete the formation of the 30 staple at the nose of said arm; and means to drive the staple from the place where it is completed.
- 35 7. A machine for use in fastening heads, ends, partitions or the like to boxes, and having an arm adapted to enter the box close to the sides thereof, said arm being constructed and arranged by engagement with a box side to position the cleat of said 40 box side with its longitudinal center line in the same vertical plane with the longitudinal center line of said arm, which comprises means successively to form a plurality of staples with the plane of their legs in 45 the same vertical plane with the longitudinal center line of said arm; and means successively to drive said staples into the work whereby a succession of staples may be driven along the longitudinal center line of 50 said cleat with the vertical plane of their legs coinciding with said longitudinal center line of the cleat.
- 55 8. A machine for use in fastening heads, ends, partitions or the like to boxes comprising, in combination, a stapling arm having parallel sides adapted to enter a box; means to feed a wire along the longitudinal center line of said arm to its nose; means to form a staple at the nose of said arm 60 with its legs vertical in the plane of the longitudinal center line of said arm; whereby the staple-forming and driving mechanism may be confined within narrow limits and a cleated box side may be positioned 65 parallel with the longitudinal center line of
- said arm with the longitudinal center line of the cleat directly over the longitudinal center line of said arm.
9. Mechanism for forming and driving staples comprising means to bend one end of a wire at right angles to the body of the wire to form one leg of a staple; means to present said leg to the staple-driving point; and means to complete the formation of the staple at the staple-driving point. 70
10. Mechanism for forming staples from a strand of staple stock wire comprising means to sever said wire and form simultaneously a leg for each of a plurality of staples. 75
11. Mechanism for forming staples from a strand of staple stock wire comprising means to sever said wire and complete the formation of one staple while partially forming another. 80
12. The process of forming and driving staples which is characterized by bending one end of a wire at right angles to the body of the wire to form one leg of a staple, presenting said leg to the staple-driving point, and bending said wire to complete the formation of the staple at the staple-driving point. 85
13. The process of forming staples from a strand of staple stock wire which is characterized by severing said wire and forming simultaneously a leg for each of a plurality of staples. 90
14. The process of forming staples from a strand of staple stock wire which is characterized by severing said wire and completing the formation of one staple while partially forming another. 95
15. A machine for use in fastening heads, ends, partitions or the like to boxes comprising, in combination, a stapling arm having parallel sides adapted to enter a box; and means for forming a staple at the nose of said arm and driving it into the work from the place at which it is formed. 100
16. A machine for use in fastening heads, ends, partitions or the like to boxes comprising, in combination, a single stapling arm having parallel sides adapted to enter a box and gauge and position the box sides during stapling operations; and means for forming a staple at the nose of said arm and driving it into the work from the place at which it is formed. 105
17. A machine for use in fastening heads, ends, partitions or the like to boxes comprising, in combination, a stapling arm having parallel sides adapted to enter a box; means to feed a wire along the longitudinal center line of said arm to its nose; means to form a staple at the nose of said arm; and means to drive the staple into the work from the place where it is formed. 110
18. A machine for use in fastening heads, ends, partitions or the like to boxes com- 115
- 120
- 125
- 130

prising, in combination, a stapling arm adapted to operate within a box; and mechanism carried thereby for partially forming a plurality of staples simultaneously.

19. A machine for use in fastening heads, ends, partitions or the like to boxes comprising, in combination, a stapling arm adapted to operate within a box; mechanism carried thereby for partially forming a plurality of staples simultaneously; and means for driving a staple into the work.

20. A machine for use in fastening heads, ends, partitions or the like to boxes comprising, in combination, a stapling arm, adapted to operate within a box; and mechanism carried thereby for partially forming a plurality of inverted staples simultaneously and for driving a completed staple upward into the work.

21. A machine for use in fastening heads, ends, partitions or the like to boxes comprising, in combination, a stapling arm adapted to operate within a box; and mechanism carried thereby for simultaneously completing the formation of one staple and partially forming another.

22. A machine for use in fastening heads, ends, partitions or the like to boxes comprising, in combination, a stapling arm adapted to operate within a box; and mechanism carried thereby for simultaneously completing the formation of one staple and partially forming another and for driving the completed staple into the work.

23. A machine for use in fastening heads, ends, partitions or the like to boxes comprising, in combination, a stapling arm adapted to operate within a box; and mechanism carried thereby for simultaneously completing the formation of one inverted staple and partially forming another.

24. A machine for use in fastening heads, ends, partitions or the like to boxes comprising, in combination, a stapling arm adapted to operate within a box; and mechanism carried thereby for simultaneously completing the formation of one inverted staple and partially forming another and for driving the completed staple upward into the work.

In testimony whereof, I have signed my name to this specification.

BRUCE J. DAVIDSON.
